STAND FOR HANUKKAH LIGHTS

Samuel R. Zoss, Youngstown, Ohio

Application February 13, 1950, Serial No. 7,910

Term of patent 14 years

(Cl. D48—20)

To all whom it may concern:

Be it known that I, Samuel R. Zoss, a citizen of the United States, residing at Youngstown, in the county of Mahoning and State of Ohio, have invented a new, original, and ornamental Design for a Stand for Hanukkah Lights, of which the following is a specification, reference being had to the accompanying drawing, forming part thereof.

Figure 1 is a top plan view of a stand for Hanukkah lights, showing my new design.

Figure 2 is a perspective view thereof.

Figure 3 is a cross sectional view, to a larger scale, taken on the line 3—3 of Figure 2.

I claim:

The ornamental design for a stand for Hanukkah lights, as shown.

SAMUEL R. ZOSS,
